HERBERT V. LECKIE AND SAMUEL A. NORTH, OF BRIDGEPORT, CONNECTICUT, AS
SIGNORS TO REMINGTON ARMS COMPANY, INC., A CORPORATION OF DELAWARE.

ANNEALING APPARATUS.

Application filed July 16, 1925. Serial No. 44,011.

This invention relates to a machine and a method of annealing metal articles, such as metallic cases for cartridges.

In the making of tubular articles, such as 5 metallic cartridge cases, the metal necessary for forming the cartridge case is struck from sheet stock, and by progressive drawing operations is formed into a tube of the requisite size and proportions. Cartridge cases are 10 commonly made of brass and since the successive drawing operations harden the brass and make it brittle, it is necessary to anneal the tube one or more times, between drawing operations, in order to prevent the tube becoming 15 so hard that it will split either during or subsequent to the operations of drawing. A section of the case adjacent to its mouth or open end, is finally drawn to a neck of reduced diameter to receive the bullet, the 20 powder containing section of the case for most rifle cartridges being of greater diameter than the bullet receiving neck. The bullet inserted into the neck is of slightly greater diameter than the neck, and its insertion 25 therein induces such stresses in the metal of the neck as to cause frequent splitting. Indeed such split necks have in the past been a very common cause of defective ammunition. The defect is aggravated by 30 the fact that it is impossible to anticipate when splits will develop.

It has been the practice in the past to anneal shell cases by passing them between rows of opposed burners. The flames of such 35 burners spread vertically on encountering the shell case and each other with the result that the shoulder at the base of the neck is softened and weakened. When such weakened 40 shoulder cases are struck by the firing pin the case will upset, destroying the force of the impact of the firing pin on the primer and causing the cartridge to misfire. The present 45 invention contemplates a means and a method of annealing cartridge cases or similar articles, whereby a definite line of demarcation between annealed and unannealed parts is secured, thereby providing that the metal will be hard and resistant where this characteristic is required, and adjacent points will 50 be soft enough to permit of stretching or other deformation without rupture.

In the drawings, Fig. 1 is a diagrammatic plan view of one form of machine by which the object of this invention is accomplished.

Fig. 2 is a transverse section, substantially 55 on the line 2—2 of Fig. 1.

Fig. 3 is a fragmentary side elevation of one form of burner.

Figs. 3^a and 3^b are respectively sections on the lines a—a and b—b of Fig. 3. 60

Fig. 3^c is a plan view of the burner shown in Fig. 3.

Fig. 4 is a section through a cartridge case annealed by the methods of the present invention. 65

The several parts of the machine to be described are supported from a pedestal or base 10. In order to secure uniform and readily controllable heating of the section of the cartridge case or other tube to be annealed, the 15 invention includes the provision of means for rotating the cartridge cases and simultaneously moving them past suitable heating devices. For this purpose a cartridge supporting, conveying and rotating member is provided, which may be in the form of a screw conveyor. The conveyor device which has 20 been illustrated, comprises a shaft 11, provided with a wheel or pulley 12, whereby the shaft may be rotated. A spiral screw or 25 worm 13 surrounds the shaft 11 and is rigid therewith, the pitch of this screw being such that the cartridge cases may rest on the shaft 11 between adjacent turns of the screw. A longitudinal bar 14 furnishes a lateral support 30 for the cartridge cases in the conveyor screw. It will be seen that as the screw is rotated, cartridge cases resting thereon, between adjacent turns of the worm will be fed 35 longitudinally of the screw and will be simultaneously rotated. 40

Adjacent to the conveyor screw, and located at a suitable height to direct a flame against the necks of the cartridge cases, is a single row of burners 15, these burners being 45 provided with tips capable of producing a flat, thin, laterally spreading flame. Any burner tip which is capable of producing a thin, flat flame may be utilized; one form of such tip is illustrated in Figs. 3, 3^a and 3^b. 50 In this tip, a restricted central passage 16 in alignment with the outlet 17 is provided, and arcuate passages 18 and 19 of larger area approach the outlet from opposite directions, these passages being so arranged that the 55 fluid streams passing therethrough are directed toward each other adjacent to the outlet opening, and are deflected outwardly 60

through the outlet by the fluid jet through the central passage 16.

In prior cartridge case annealing machines, it has been customary to provide two sets of 5 burners directing flames against the opposite sides of the cartridge cases, which were conveyed between such flames. In such a device, the vertical spreading of the flame is inevitable, and an accurate control of the area of 10 the shells annealed thereby is impossible. By providing means for rotating the shells, as they are moved past a single line of flat flames, a very accurate control of the area annealed is secured.

15 The section shown in Fig. 4 was prepared from a shell which had been annealed in the machine described. A very definite line is seen to separate the annealed and unannealed part of the shell.

20 Any suitable means for supporting the burners and conducting a combustible fluid thereto may be provided. In the particular device illustrated, a mixture of gas and air is supplied to the burners 15 through the 25 branch T 20, which connects with the mixing tube 21, to which gas and air are supplied through the connecting tubes 22 and 23. Means are provided for permitting an accurate vertical adjustment of the burners. 30 To this end the burner assembly may be mounted in supporting arms 24, pivoted at 25 to ears extending upward from brackets 26. Rearward extensions 27 of the arms 24 are perforated to receive screws 28 which 35 extend upward from the bracket 27, and an adjusting nut 29 and a spring 30 locate the arms 27 on the screws 28. A fine adjustment of the burners is thereby provided. Each of the brackets 26 is adjustably supported from 40 the pedestal 10 by means which may be constructed as follows. The downwardly extending arm 261 of each bracket 26 is received in a recessed support 31 on the base. Said arm 261 is perforated to receive the pin 45 32 which may be inserted through any one of a plurality of perforations 33 in the support 31.

50 Any suitable means may be provided for feeding cartridge cases into the machine in proper relation to the conveyor screw. For example, cartridge cases may be contained in a hopper located above and adjacent to the annealing machine, and may pass through a tube 34 to a position adjacent to the conveyor screw. A suitable transversely moving plunger 35 may be connected through a link 55 36, eccentric 37 and gears 38 and 39 to the shaft 11, the plunger 35 being thus recipro-

cated during each rotation of the shaft 11, a cartridge case is moved thereby over the 60 shaft 11 and into the screw 13, which at this point is of reduced diameter. A second screw 40 may be placed substantially in alignment with the supporting bar 14 to support the 65 side of the cartridge cases as they are received on the shaft 11, and move them into engagement with the supporting bar 14. Having traversed the conveyor screw, the cartridge cases may be received in a suitable device, such as a chute 41, having an extending guiding wing piece 42 which, with the last turn 70 of the worm 13 guides the cases into the chute.

The embodiment of the invention shown and described is to be understood to be illustrative rather than restrictive, the invention being limited only by a broad construction of the appended claims.

We claim:

1. In a cartridge case annealing machine, a screw conveyor adapted to translate and simultaneously rotate cartridge cases, and heating means adjacent to said conveyor adapted to heat a definite section only of said cartridge cases.

2. In a cartridge case annealing machine, a screw conveyor adapted to translate and simultaneously rotate a cartridge case, heating means adjacent to said conveyor adapted to heat a definite section only of said cartridge cases, and means for adjusting said heating means to select the section of the cartridge cases to be heated thereby.

3. In a cartridge case annealing machine, in combination, a conveyor adapted to simultaneously translate and rotate cartridge cases, a bar for laterally supporting the cartridge cases in said conveyor, and a cartridge case feeding screw in alignment with said supporting bar, and adapted to move cartridge cases into engagement therewith.

4. In a cartridge case annealing machine, a screw conveyor adapted to receive cartridge cases in radial positions between adjacent threads thereof, the thread of said screw conveyor adjacent one end thereof being of reduced diameter, a cartridge case supporting and feeding worm located adjacent said end of said screw, and cooperating with said thread of reduced diameter to move the cartridge cases into engagement with the full diameter threads of said screw, and means for transferring cartridge cases from said delivering means into engagement with said worm and said reduced diameter thread.
